UNITED STATES PATENT OFFICE

JOHN L. McMILLAN, OF SYRACUSE, NEW YORK, ASSIGNOR TO McMILLAN BOOK COMPANY, OF SYRACUSE, NEW YORK, A CORPORATION OF NEW YORK

INDEX LEAF

Application filed June 4, 1928. Serial No. 282,737.

This invention relates to a new and improved index leaf for visible index binders.

When a loose leaf binder is used as a visible index the sheets in the binder are less in height than the over-all height of the binder so that they may be positioned in the binder in overlapping arrangement whereby a portion of each sheet is exposed so that the indicia carried by it may be at all times in sight.

It is also customary when using loose leaf binders as visible indices to make use of indexing leaves so as to separate into groups or alphabetical divisions the sheets in the binder. These leaves are usually the same height as the height of the binder so that they cover all of the sheets in the portion for which they are the indices.

When sheets are assembled in a binder in overlapping relation the number of sheets superimposed upon each other will vary at different points in the binder. That is to say, there will be fewer sheets superimposed one upon the other at the top and at the bottom of the binder than will be the case at the intermediate portion of the binder. This being the case the thickness of the book will be greater in the middle portion than it will at the top and the bottom which will result in a distortion of the binder which will render the same unsightly and less convenient to use.

The main object of my invention is to construct indexing leaves of such a shape and size that they will in themselves compensate for the different thicknesses of the book and will insure a book of even thickness throughout its height.

In loose leaf binders which are used as visible indices there is usually provided a means for transferring sheets vertically of the binder without the necessity of removing the sheets from the prongs on which they are carried. In one type of binder having a transferring device the prongs carried by one of the back members of the binder are pivoted so that they may be swung sidewise and their position changed in relation to the opposing prongs as disclosed in an application filed by me for loose leaf binder, March 14, 1928,

Serial No. 261,532, and a further object of my invention is to construct indexing leaves which will prevent the closing of the binder when the prongs are in the transferring position.

Other objects and advantages relate to the size, shape and arrangement of parts all as will more fully appear from the following description taken in connection with the accompanying drawings in which:

Figure 1 is a perspective view of my indexing leaf.

Figure 2 is a section on line 2—2 of Figure 1.

Figure 3 is a section on line 3—3 of Figure 1.

Figure 4 is a top plan view, partially broken away, showing an indexing leaf in position in a binder.

Figure 5 is a perspective view of a modified form of my device.

Figure 6 is a section on line 6—6 of Figure 5.

Figure 7 is a section on line 7—7 of Figure 5.

My indexing leaf —1— may be varied in size and shape to fit the particular binder with which it is to be used but in each instance it consists of a main body portion —2— usually provided on one longitudinal edge with a tab —3— upon which indicia may be placed, it being understood that the position of tabs 3 on the indexing leaves, which are used in a binder, may be varied so that when the indexing leaves are in position in a binder all of the tabs 3 will be exposed to view. The ends of body —2—, as perhaps may best be seen from Figure 3, are return bent on themselves so that they will form ends —4— and —5— in spaced relation, which ends —4— and —5— will be double the thickness of the remaining part of body —2—. The double thick ends 4 and 5 extend inwardly from the outer edge of body 2 and terminate a short distance from the inner edge of body 2 so that the full lengths of such inner edge consists of only one thickness of body 2.

As perhaps may best be seen from Figure 2, I provide tabs —6— of the same width as ends —4— and —5—. Tabs —6— are formed

of a single piece of leather or other appropriate material return bent on itself and having in its outer end a reinforcing plate —7— of tin or other appropriate material. The edge 5 of body —2— which is adjacent end —4— is inserted between the open edges of a tab —6— with the upper edge of tab —6— abutting against the end of end —4— and the tab —6— is then fastened in position by gluing 10 or other convenient means. A similar tab —6— is affixed to body —2— adjacent end —5— in a similar manner. Tabs —6— are provided with a plurality, in this case shown as five, of spaced apertures —8— extending 15 through the outer edge of tab —6— in which the reinforcing plate —7— is positioned. As perhaps may best be seen from Figure 4, apertures 8 are provided so that the indexing leaf —1— may be placed on prongs 9 of a 20 loose leaf binder.

The distance between the centers of apertures 8 is twice the distance between the centers of the apertures 10 with which the sheets 11 of the binder are provided with the result 25 that when the prongs 12 of a transferring binder 13 are rotated to either of the positions indicated in dotted lines on Figure 4, the binder cannot be closed because there will be no apertures 8 in indexing leaf —1— into 30 which prongs 12 may enter which will be notice to the operator that the prongs 12 must be returned to the normal position before the book can be closed.

In Figures 5, 6, and 7 I have shown a modification of my device which comprises a body 35 —14— having the usual indexing tab —19— but in order to provide thicker ends similar to ends —4— and —5— I form a tab —15— made of a single piece of leather or other appropriate material and return bent on itself. A reinforcing plate —16— of tin or other appropriate material is provided in the closed 40 end of tab —15—. The length of tab —15— is such that when body —14— is inserted into the open end of tab —15— with one edge adjacent the end of body —14— tab —15— will extend the full width of body —14— with its closed end extending outwardly from the edge of body —14—. Tab —15— is securely 45 fixed in this relation to body —14— by the use of glue or other convenient means. Tab 50 15 is provided with a plurality, in this case shown as five, of apertures —17— in the end which carries the reinforcing plate —16— and which are for a use similar to the use for which apertures 8 were provided in tabs 6. It will be understood that a tab —15— is affixed on body —14— at each end thereof so 55 that the indexing leaf —18— will have opposed ends which are thicker than that part of body —14— which is positioned between them. The apertures —17— are spaced in a manner similar to the manner in which the apertures 8 are spaced so that my modified 60 form of indexing leaf will function in a

binder in a manner similar to the manner in which the first described indexing leaf functions.

It will be understood that the materials of which my indexing leaf and the different parts thereof are constructed may be varied as desired, and it will also be understood that the thickness of the ends of my indexing leaf compared to the thickness of the main body thereof may also be varied depending upon the type of binder with which my device is to be used and the number and position of the sheets normally carried by that particular binder. The width of the thickened ends of the indexing leaf may also be varied so that they may be adapted for use with different types of loose leaf binders, for although I have shown and described a specific structure and form and relation of parts as an exemplification of an embodiment of my invention I do not desire to restrict myself to the exact size, shape or relation of parts as various changes may be made within the scope of the appended claims.

I claim:

1. In a device of the class described, a body portion, relatively thick opposed end portions, and a tab having a plurality of spaced apertures extending laterally from each of the end portions.
2. In a device of the class described, a body portion, relatively thick opposed end portions, an index tab extending laterally from one longitudinal edge of the body portion, and a tab having a plurality of spaced apertures extending laterally from each of the end portions.
3. In a device of the class described, a body having a portion of each end return-bent upon itself to form double thick end portions, an index tab extending laterally from one longitudinal edge of the body, and a tab having a plurality of spaced apertures extending laterally from each of the double-thick end portions on the opposite longitudinal edge of the body.

In witness whereof I have hereunto set my hand this 29th day of May, 1928.

JOHN L. McMILLAN.
